UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

WATCH-FOB.

1,370,125.

Specification of Letters Patent.

Patented Mar. 1, 1921.

Application filed October 29, 1919. Serial No. 334,238.

To all whom it may concern:

Be it known that I, JOSEPH KOMOROUS, a citizen of the United States, residing at Chicago, in the county of Cook and State 5 of Illinois, have invented a new and useful Improvement in Watch-Fobs, of which the following is a specification.

My invention relates, as to a certain feature thereof, to an improvement in watch 10 fobs, my object in this connection being to provide a novel and simple construction of device for use more particularly as an advertising novelty; and also as to another feature thereof, generally, to the provision 15 of means, in the nature of a buckle device, for attaching to a body, as for example a watch fob medallion, a flexible suspending element, as for example a strap, and my object in this connection is to provide novel, 20 simple and economical means of this character, and preferably so constructed as to prevent disengagement of the suspending element therefrom.

Referring to the accompanying drawings:—Figure 1 is a face view of a watch 25 fob embodying my improvements. Fig. 2 is an edge view thereof. Fig. 3 is a face view of the medallion portion of the watch fob; and Fig. 4, a broken, enlarged, section 30 taken at the line 4 on Fig. 1 and viewed in the direction of the arrow.

In the particular construction shown, 5 represents the medallion portion of a watch fob, which may be ornamented or not as 35 desired, and which as shown is formed with a raised circular part 6 on which any suitable design or legendary or display matter may be presented, as for example by forming it of a circular disk secured to the portion 5 in any desirable manner and covered by celluloid through which the matter provided on the outer face of the disk referred to may be viewed. The portion 5 may be made of any suitable material, as for example 40 metal or fiber, and in accordance with one of the features of my invention, is provided integrally therewith with means indicated at 7, and in the nature of a buckle device, for securing to the medallion 5 the 45 flexible suspending element of the fob, this element being represented at 8 and shown as formed of a strap folded upon itself to present the loop 9, its opposite end being secured to the buckle device 7. The buckle 50 device as shown is formed by providing in

the medallion 5, preferably partly in an extension 10 of the medallion, a pair of slots 11 and 12 which are arranged in parallel relation and are separated from each other by a bar-section 13, the bar-section 13 and 60 the outer cross-member, or bar-section, 14 of the buckle device being equipped with tits 15 and 16 located preferably midway between the ends of the slots 11 and 12 and projecting part way through the latter, the 65 distance from the extremity of the tit 15 to the wall 17, which latter is preferably slightly curved, and the distance from the extremity of the tit 16 to the wall 18, which latter is also preferably slightly curved, in 70 each instance being less than twice the thickness of the material of which the strap portion 8 is constructed.

In accordance with the preferred embodiment of the invention, the strap portion 8 is 75 looped as hereinbefore stated and its free ends connected with the medallion 5 by threading them through the slots 12 and 11 and interlocking them with this part of the device. One of the free ends of the 80 strap represented at 19 contains an aperture 20 and the other free end 21 of the strap contains an aperture 22. In connecting the strap with the medallion as shown, the end portion 19 is first threaded through the slot 85 12 from the back of the medallion and this part of the strap interlocked with the tit 16 at the opening 20 therein as shown in the drawing. The other end portion 21 is then introduced from the back of the medallion 90 through the slot 12 and then introduced from the front side of the medallion into the slot 11, the tit 15 entering the opening 22 therein, the free end 19 being then introduced from the front side of the medallion 95 through the slot 11. It will be understood that by reason of the proportioning of the slots 11 and 12 relative to the tits 15 and 16, as stated, the end portions 19 and 21 cannot possibly disengage from the tits 16 100 and 15, respectively, and thus the element 8 is securely held in assembled position with the medallion 5.

As regards the feature of the construction of the buckle device shown, it will be 105 understood that the invention is not limited to threading the strap in the particular way shown.

While I have illustrated and described a particular construction embodying my inven- 110

tion, I do not wish to be understood as intending to limit it thereto as the same may be variously modified and altered without departing from the spirit of my invention.

5. What I claim as new and desire to secure by Letters Patent is:

1. A buckle device comprising a member containing a plurality of slots with projections extending adjacent said slots, and a flexible element presenting end portions each containing an opening, said end portions extending into said slots, with said projections extending into said openings, the distance between the extremities of the projections and the respective opposing walls of the slots adjacent to the projections being less than the combined thickness of the two end portions of said element extending into said slots, each of said end portions extending into both of said slots.

2. A buckle device comprising a member containing a plurality of slots with projections extending adjacent said slots, and a flexible element presenting end portions each containing an opening, said end portions extending into said slots, with said projections extending into said openings, the distance between the extremities of the projections and the respective opposing walls of the slots adjacent to the projections being less than the combined thickness of the two end portions of said element extending into

said slots, one of said end portions at an unperforated part thereof extending into one of said slots between the one of said projections adjacent thereto and the wall of the slot opposing the latter, and the other of said end portions at an unperforated portion thereof extending into the other of said slots between the projection adjacent thereto and the wall of the slot opposing the last referred to projection.

3. A watch fob having a medallion portion provided with a plurality of slots adjacent its edge, and projections extending into such slots, said projections extending in the same direction.

4. In a watch fob, an enlarged portion forming a medallion and having a relatively smaller neck-portion extending therefrom, slots in said smaller portion, and projections extending in the same direction and partially across said slots.

5. A buckle device comprising a member containing a plurality of slots, projections adjacent said slots and extending partially across the same, said slots and projections being so proportioned that the combined thickness of two strap portions when threaded through said slots will be greater than the distance from the extremity of the projections and the opposite wall of the slot toward which they extend.

JOSEPH KOMOROUS.
